HOUSING FOR A WINDOW VENTILATOR

Paul Wrablica, Jr., New York, N. Y.

Application April 28, 1954, Serial No. 30,239

Term of patent 14 years

(Cl. D62—4)

FIG. 1

FIG. 2

To all whom it may concern:

Be it known that I, Paul Wrablica, Jr., a citizen of the United States of America, and resident of the county of Queens, city and State of New York, have invented a new, original, and ornamental Design for a Housing for a Window Ventilator, of which the following is a specification, reference being had to the accompanying drawing, forming a part thereof, and which

Fig. 1 is a front perspective view of a housing for a window ventilator embodying my design; and
Fig. 2 is a side view thereof.

I claim:

The ornamental design for a housing for a window ventilator, as shown.
